UNITED STATES PATENT OFFICE.

LEWIS E. MORRISON, OF NEWARK, NEW JERSEY, ASSIGNOR TO AUTOMATIC PLATEN PRESS COMPANY, OF NEW YORK, N. Y., A CORPORATION OF NEW JERSEY.

SHEET-FEEDING MECHANISM.

1,014,323.

Specification of Letters Patent.

Patented Jan. 9, 1912.

Original application filed January 2, 1907, Serial No. 350,516. Divided and this application filed January 17, 1908. Serial No. 411,247.

To all whom it may concern:

Be it known that I, LEWIS E. MORRISON, a citizen of the United States of America, and a resident of the city of Newark, county of Essex, State of New Jersey, have invented certain new and useful Improvements in Sheet-Feeding Mechanisms, of which the following is a specification.

This invention relates to sheet feeding mechanisms for separating the bottom sheet from a pile and presenting the thus separated sheet to any adjacent machine or mechanism such as for instance a printing machine.

15 The subject matter of this invention is divided out from application for improvements in printing machines patented May 30, 1911, Number 993,612.

20 The object of this invention is to provide a sheet feeding mechanism of an improved high speed type, and the particular improvements reside in the novel features, elements of construction as well as the mode of operation, which contribute to the desired 25 result, and which will be pointed out fully in the claims, while the following detailed description and the accompanying drawings clearly set forth and illustrate my invention in detail.

30 In the said drawings Figure 1 is a side elevation of a printing machine equipped with my feeding mechanism. Fig. 2 is a side elevation of a feeding mechanism embodying my invention. Fig. 3 is a plan view of the same, while Figs. 4, 5 and 6 are detail views 35 of the suction mechanism which I employ.

Referring to Fig. 1 which shows the printing machine described in the above cited application, it should be kept in mind that it 40 is shown for the purpose of this disclosure only and that all unnecessary details have been omitted. In the said figure, the reference numeral 1 indicates the general frame for supporting the various parts, while 2 indicates the main driving shaft to which power is supplied in any convenient form. The form carrying member is denoted by 4 while 5 is the stationary platen. The form member is in this instance supported in 45 swinging arms 6 pivoted on the stationary shaft 7. The feeding mechanism is indicated by 8 and the registering mechanism by 9. For the detailed construction of this ma-

chine I refer to the above mentioned application.

Referring now to the other figures, the reference numeral 10 denotes the pack or pile of sheets to be separated and fed and which is supported in the reciprocating carriage or frame 11. This carriage is preferably a square or rectangular framework as shown and to properly position the sheets therein, side gages as 12, 13 and a rear gage 14 are provided. These gages are adjustable as shown and may be of any suitable or convenient construction, the rear gage is provided with fingers as 15 for the support of the rear edges of the sheets, the body of which rests directly on a plurality of rollers 16. These rollers are preferably of hard wood or similar material, well finished, and are pivoted in the side frames 17 in such a manner that they will rotate freely, that is, these rollers are not in frictional contact with one another. The frames 17 form the main support of the feeding mechanism and are suitably fastened to the shaft 7. The carriage travels in grooves 18 in the frames 17 and the rollers 16 are grooved as at 19 to permit free passage of the fingers 15.

25 The suction mechanism which I employ to separate the bottom sheet from the pack is carried by one of the rollers 16, in the drawing indicated by 20. This roller is provided with a plurality of grooves 21 in which rest the branches 22 of the suction pipe 23 in such a manner that they form no obstruction to the passage of the sheets over the rollers. Suction is applied by means of the pump 24 connected to the pipe 23 by the flexible connection 25. The operating mechanism for the pump is not shown as the same may be of any convenient type easily supplied by those skilled in the art. The suction is of course, applied once to every revolution of the machine. As will be later on pointed out the suction pipes oscillate independently around the roller 20. To this end the one end of the pipe 23 is closed with a rod 26 which extends through a slot 27 in the one side frame and which, outside the latter, is fast in the one arm of a bell crank 28, which is pivoted on the pin 29 in the frame. The other arm 30 of the said bell crank extends upwardly and is adapted to be acted upon by the cam 31 on the one side.

of the carriage. The spring 32 keeps the bell crank and the suction pipes in their normal position. From this it will be seen that as the carriage advances the cam will engage the arm 30 and the suction pipes will oscillate downwardly.

Before describing the operation of the mechanism, it should be noted that the carriage is reciprocated by means of the links 10 33 pivotally connected to the ends of the arms 34, see Fig. 1, which are fast on the rock shaft 35, which latter is rocked through the instrumentality of the arm 36 fast on said rock-shaft and connected to the bar 37 15 carrying cam roll 38 coöperating with cam 39 on shaft 40 driven from the main shaft through pinion 41 and gear 42, so that the carriage reciprocates once to every revolution. Adjacent the roller 20 there is further 20 located the two guide or feed rolls 43, 44, which rotate constantly in two opposite directions and one of which is driven positively by being extended through the side frame, outside of which it carries the pinion 45, 25 which is driven from the main shaft 7 by the intermediate gear 46. Above the roll 43 there is fixed a separating shield 47, which may be carried by the transverse rod 48 or otherwise fixed. The two guide rolls are of 30 course so placed that they do not touch the adjacent other rollers.

The operation is as follows: The pack of sheets are placed and positioned in the carriage, so that their front edges rest preferably directly over the openings of the suction pipes 22. As the carriage starts upon its travel, the suction is applied and the lowermost sheet separated. At the same time the cam 31 acts to oscillate these pipes 40 downwardly. The suction then ceases and by the continued motion of the carriage the bottom sheet is fed into the bite of the feed rollers and from thence out in the direction of the arrow in Fig. 2 and onto whichever 45 mechanism is next to act upon it. The carriage continues to travel over the other rollers 16, the pack of sheets riding over the separating shield 47, the cam 31 keeping the suction pipes all the time turned down. The 50 pack of sheets will be so adjusted in the carriage that they will pass clear out over the suction roller on the movement to the right in Fig. 2, because the bottom sheet must be given time to pass completely away from 55 underneath the sheets before these latter, on the movement to the left, again pass over the suction roller, hence the layer of rollers extends for a distance at least twice as long as the length of the longest sheet to be handled 60 by the press. Next the carriage returns to its starting position and the mechanism is ready to act upon the next sheet.

It is thought that the above clearly describes my invention and the mode of operation. It will be seen that the sheets move all

the time upon a rotating support composed of the layer of rollers which rotate in either direction as the carriage reciprocates, so that there is no or very little friction, also that the suction mechanism proper is operated 70 independently of the other mechanism while the feed rolls are constantly rotated independently of the motion of the other rollers. It has been found in practice that this feeding mechanism operates with very little 75 noise and with great accuracy. By reason of the upward run of the pack of sheets, it hardly ever happens that more than one sheet is separated.

The above construction is of course, susceptible of many changes, but I claim all of these, that may come under the scope of this invention and the following claims.

What I claim is:

1. In a sheet feeding device the combination of a layer of pivoted rollers for supporting the sheets, a separating mechanism carried by one of the said rollers in the center of the said layer, means for reciprocating the stack of sheets on the said layer and means for operating the said separating mechanism by the said reciprocating means. 80

2. In a sheet feeding device the combination of a sheet separating means, a layer of rollers extending on either side of the 95 said means and mechanism for reciprocating the sheets on the said layer of rollers.

3. In a sheet feeding device the combination of a sheet separating means, a layer of rollers extending on either side of the said 100 means, and mechanism for reciprocating a pack of sheets on the said rollers and for operating the said separating means.

4. In a sheet feeding device the combination of a separating mechanism, means for 105 moving a pack of sheets over and past the said mechanism and rotatable members for supporting the sheets on both sides of the said mechanism.

5. In a sheet feeding mechanism the combination of a separating device, means for moving a pack of sheets over and past the said device, rotatable members for supporting the sheets on both sides of the said device, and means for oscillating the latter 115 from the said moving means.

6. In a sheet feeding mechanism the combination of a reciprocating carriage adapted to receive a pack of sheets, a layer of rotatable rollers for supporting the said 120 sheets, a separating mechanism carried by one of the said rollers, means for oscillating the said mechanism independently of its supporting roller, a plurality of feed rolls and means for operating the latter. 125

7. In a sheet feeding mechanism the combination of a reciprocating carriage adapted to receive a pack of sheets, means for moving and guiding the said carriage, means for separating the lowermost sheet, 130

means for actuating said separating means from the said carriage, a plurality of rollers supporting the said sheets and adapted to rotate in the same direction as the said carriage travels, a fixed separating shield interposed between the said separating means and one of the said rollers, a pair of positively driven feed rolls and means for operating the latter constantly in one direction.

8. In a sheet feeding device the combination of a separating mechanism, means for moving a pack of sheets over the same and a layer of rotatable rollers extending on either side of the said mechanism and adapted to rotate in the same direction as the sheets travel and to remain at rest when the sheets are at rest.

9. In a sheet feeding and separating device the combination of a reciprocating carriage adapted to receive a pack of sheets,

separate means for supporting the edge of the sheets in the said carriage, a layer of pivoted rollers for supporting said sheets both when the carriage is in motion and at rest and provided with grooves to permit the free passage of the aforesaid edge supporting means, a separating mechanism comprising suction pipes and means for oscillating the same by the action of the said carriage, the said separating mechanism being mounted on one of the said rollers, a fixed sheet separating shield adjacent the said separating mechanism and a plurality of driven feed rolls.

Signed at New York, N. Y., this 11 day of Jan., 1908.
